BANQUET COVER

David L. Painter, Evanston, Ill., assignor to Aluminum Company of America, Pittsburgh, Pa., a corporation of Pennsylvania

Application January 7, 1953, Serial No. 23,054

Term of patent 14 years

(Cl. D44—15)

To all whom it may concern:

Be it known that I, David L. Painter, a citizen of the United States, residing at Evanston, in the county of Cook and State of Illinois, have invented a new, original, and ornamental Design for a Banquet Cover, of which the following is a specification, reference being had to the accompanying drawing, forming a part thereof, in which:

Fig. 1 is a top plan view of a banquet cover embodying my new design; and

Fig. 2 is a partial side elevational, partial vertical sectional view thereof.

I claim:
The ornamental design for a banquet cover, substantially as shown.

DAVID L. PAINTER.
